UNITED STATES PATENT OFFICE

SAMPSON W. MOON, OF CHICAGO, ILLINOIS

ELECTRIC VIBRATORY DEVICE

Application filed March 19, 1928. Serial No. 262,686.

My invention relates to electric vibratory devices, particularly electric safety razor and massage devices.

An important object of the invention is to provide a structure in which the support for a tool, such as a razor blade or massage element, is entirely free from direct mechanical movement or impact engagement by an armature, but to which vibration is transmitted reactively by a freely vibrating armature whose vibration cannot be interrupted by abnormal use of the tool, such as excess pressure.

Another object is to produce a simple and compact structure which can be economically manufactured and which is electrically shock proof and whose internal operating parts are protected from dirt and moisture.

The above and other features of construction and operation are embodied in the structure shown on the drawing in which:

Fig. 1 is a plan view with the grip shell in vertical section;

Fig. 2 is a side elevation with the supporting heads and grip shell in vertical section;

Fig. 3 is a section on plane 3—3 Fig. 2;

Fig. 4 is a section on plane 4—4 Fig. 2, and

Fig. 5 is a plan view of the front end of the device with the front head in section, and showing a modified form of tool supporting post.

The structure comprises front and rear heads 10 and 11 of insulating material, between which extends the electromagnet core 12 which threads into the front head and is secured to the rear head by a screw 13. Insulating washers 14 and 15 confine the energizing winding 16 on the core.

Above the core a spring 17 is secured to the rear head, preferably by being molded therein, and this spring extends a distance forwardly and terminates in a sleeve 18 for receiving and securing the rear end of the armature bar 19. This bar extends forwardly above the core and at its front end has the tongue 20 extending downwardly past and at one side of the pole end of the core between the washer 14 and the head 10. This tongue is curved longitudinally, as shown, to decrease

the magnetic resistance between the tongue and the cylindrical pole end.

Near its rear end the armature bar has the contact point 21 for cooperating with the contact spring 22 whose base 23 is deflected and seats in the channel 24 in the head 11, and is there secured by a nut 25 on the inner end of the terminal pin 26 which is embedded in the head and extends a distance rearwardly thereof. A companion terminal pin 27 is embedded in the head 11 and projects therefrom adjacent to the pin 26, these pins receiving a suitable supply circuit terminal socket (not shown).

The pin 27 is deflected radially to extend within the channel 28 at the inner end of the head 11, the inner end of the pin being deflected forwardly to have soldered thereto one terminal of the energizing winding 16 whose other terminal connects with the armature contact 21. This contact and spring 22 form the circuit make and break mechanism when a direct current circuit is connected to the terminal pins, and the armature bar will be rapidly vibrated in the well known manner. The adjustment of the armature supporting spring 17 and the make and break mechanism is such that the armature tongue 20 will not strike the core pole end but will vibrate entirely free. Such free impactless vibration is transmitted reactively to the core pole end and the head 10 to which it is secured.

A tool supporting post 29 extends axially from the head 10, and in the arrangement of Figs. 1 and 2, this post is inflexible and is securely anchored at its inner end by being molded into the head. The outer end of the post is threaded to receive suitable tools. In Fig. 1 it receives the socket 30 on the frame 31 for supporting a safety razor blade 32. It is evident that massaging or other tools could be applied to the post instead of razors.

The head 10 has the reduced inner end 33 which is threaded to receive the front end of the enclosing or grip shell 34 which is slipped over the rear head 11 and has the axial passage 35 in its rear wall for receiving and protecting the ends of the terminal pins 26 and 27. A washer 36 is preferably inserted be-

tween the shell end and the head 11 to seal the shell against the entrance of moisture or dirt.

In the modified arrangement shown in Fig. 5 the tool supporting post extends from the pocket 37 and comprises the base 38 and the body 39 between which is a flexible section or spring 40 which may be integral with the base and body. The base has the threaded stud 41 which may detachably engage in a threaded opening in the head or may be securely molded therein. The threaded lug 42 on the body 39 serves to receive the tools to be operated.

The spring 40 makes the tool supporting post resilient and yieldable and smooths out and more or less softens the vibrations of the tool.

When a shaving tool is applied the vibrations of the armature are reactively transmitted to the head 10 and through the post to the shaving tool, and the blade is vibrated or oscillated longitudinally so that its edge will cut the hair and not pull it. At the same time a soothing massage is given. The blade could be omitted and the frame 31 could be used as the massaging tool, or special massaging cups or other devices could be applied to the post. As the armature vibrates entirely freely and without impact, the reactive vibrations will cause operation of the tool which is smoother and more desirable than where the tool is mechanically driven or subjected to vibration impact as is the case in prior devices of this class. Such freedom from direct mechanical cooperation between the armature and tool also makes it impossible to stop or interfere with the vibratory movements of the armature by abnormal use of the tool, such as excessive pressure.

Where the tool supporting post is resilient, as by the interposition of a spring 40, the operation of the tools will be more elastic and softened without detracting from the power of the vibration.

As the entire enclosing or grip structure is of insulating material and as the tool supporting post is entirely insulated by the head 10 from all metallic operating parts, there is no possibility of the user receiving shocks. The structure is also entirely sealed and protected against the entrance of dirt or moisture.

Having described my invention, I claim as follows:

1. In a device of the class described, the combination of a front head and a rear head, an electromagnet core extending between said heads and having an energizing winding, an armature parallel with said core, a spring extending from the rear head and secured to the rear end of the armature to support it for vibration, the front end of the armature being deflected to extend alongside of the adjacent core pole end, and a tool supporting post secured on and extending from said front head independently of said armature.

2. In a device of the class described, the combination of a grip frame, electromagnet mechanism within said frame having a freely impactless vibrating armature, and means for securing a tool to the head of said frame. 70

3. In a device of the class described, the combination of an electromagnet core having a winding, front and rear heads secured to said core, a spring anchored at its rear end in said rear head, an armature bar secured at its rear end to the front end of said spring and terminating at its front end adjacent to the front end of the core to be subjected to the magnetic action thereof and to be laterally vibrated, said spring being adjusted to prevent impact of said armature bar and core, means controlling the current flow through said winding, and a tool supporting member extending from said front head. 80

4. In a device of the class described, the combination of a grip frame, an electromagnet structure within said frame comprising an armature supported to vibrate laterally to impart vibration to said frame, a tool supporting post rigidly seated in and extending from one end of said frame independently of said armature support, and a tool at the outer end of said post, said post having an intermediate spring section of sufficiently reduced thickness to render said post laterally flexible in the direction of vibration of said armature. 90

5. In a device of the class described, the combination of a grip frame, an electromagnet structure within said frame comprising an armature supported to vibrate to impart vibration to said frame, and a post comprising a base rigidly seated in one end of said frame independently of said armature support and an outer tool supporting part, and a spring interposed between said base and outer part whereby said post is laterally flexible. 100

6. In a device of the class described, the combination of a supporting structure comprising front and rear heads, an electromagnet structure extending between and secured to said heads and comprising a core and a winding, an armature, a spring anchoring said armature at one end adjacent to one end of said core, the other end of said armature being subjected to the magnetic action at the other end of said core to be vibrated laterally, said spring being gauged to prevent impact of said armature with said core or said supporting structure so as to impart vibration only reactively to said supporting structure, and a tool secured to and extending from said front head to partake of the reactive vibration of said supporting structure. 110

In witness whereof, I hereunto subscribe my name this 12th day of March, 1928.

SAMPSON W. MOON. 130
